COMBINATION SINGLE AND DOUBLE BREASTED GARMENTS

Ralph E. Berman, Brooklyn, N.Y., assignor to Petrocelli Clothes, Inc., New York, N.Y., a corporation of New York

Filed Feb. 21, 1967, Ser. No. 617,670
5 Claims. (Cl. 2—96)

ABSTRACT OF THE DISCLOSURE

A garment of the jacket or coat variety, the lower vertices of whose lapels extend to about the waistline where they coincide in a point on the vertical front center line of the garment. Downward from said point, the right and left front panels have flaps extending therefrom to the bottom edge of the garment and beyond said center line for over and underlap and for buttons and button holes. These flaps are preferably stiffened to prevent their curling. From above said point, the appearance of the garment is that of the single breasted type, and below said point, the appearance is that of a double breasted garment.

The present invention relates to wearing apparel and more particularly to jackets and coats.

Heretofore, these garments were either single breasted or double breasted. In garments of the single breasted style, the lapels extend down to about waistline region and there they slightly overlap. A comparatively long triangular section of the shirt is exposed as well as a considerable length of the wearer's tie. The front panels of the garment overlap slightly to afford buttoning, down from the lower ends of the lapels. The fit of the garment is rather loose at and lends no support to the abdomen of the wearer, and because the lower front corners of the front panels are convexedly rounded forming an inverted V-shaped space between them, the fly of the trousers on the wearer, is exposed. In garments of the double breasted variety, the lapels intersect so high up that very little of the shirt and tie are exposed, but the overlapping of the front panels to the bottom edge of the garment, offer a girdle effect to support the abdomen. The bottom edge of each of the front panels is horizontal, hence the fly of the trousers is covered.

It is therefore the principal object of this invention to provide a novel and improved construction for garments of the character described, which will present the appearance of both a single and a double breasted garment and offer their advantageous features.

A further object thereof is to provide a novel and improved combination garment of the kind described, which is elegant in appearance, reasonable in cost to manufacture and whose construction is efficient in carrying out the purposes for which it is designed.

Other objects and advantages will become apparent as this disclosure proceeds.

In the accompanying drawing forming part of this specification, similar characters of reference indicate corresponding parts in all the views.

FIG. 1 is a front view of a garment embodying the teachings of this invention. Here, the garment is shown buttoned.

FIG. 2 is a similar view showing the garment unbuttoned. One of the front panels is shown swung so as to expose its back surface.

FIG. 3 is a fragmentary section taken at lines 3—3 or 3—3' in FIG. 2.

In the drawing, the numeral 15 designates generally a jacket whose front panels 16 and 17 are folded back to form the lapels 18, 19 as downward extensions of the

2

collar. Said lapels are of inverted triangular shape. Lapel 18 is in front of and overlaps the right front panel 16. Lapel 19 is in front of and overlaps the left front panel 17. These lapels extend convergently downward to a point 20 near the waistline region on the vertical center line of the garment, at which point the lower vertices of said lapels coincide when the garment is buttoned as in FIG. 1. The appearance of this much down to said point 20, is that of a single breasted garment. The lower vertex of the lapel 18 is indicated by the numeral 18', while that of the lapel 19 is indicated by the numeral 19'.

From the point 18', the front panel 16 has a substantially rectangular flap 16' extending to the bottom edge of the garment and away from the right side of the garment. From the point 19', the front panel 17 has a similar flap 17' extending to the bottom edge of the garment and away from the left side of the garment. When the garment is buttoned, the flap 16' is overlapped by and behind the front panel 17, while the flap 17' overlaps and is in front of the front panel 16. The entire bottom edge 21 of the garment is in a substantially horizontal plane. The flap 17' is provided with a button hole 21 near its top edge, and another button hole 22 spaced below hole 21. The panel 16 has the buttons 21', 22' sewed on the front thereof for engagement in said button holes respectively so that the flaps shall lie flat when the garment is buttoned. The button hole 22 and its button 22' are optional, and also it is optional to provide the buttons 23, 23' in positions as shown. The appearance of the garment down from the point 20, is that of the double breasted variety. Including the buttons at 23 and 23', adds to the double breasted effect. The back 24 of the garment is ordinary. On the front of the panel 17, are of course sewn the buttons 21" and 22", respectively opposite the buttons 21', 22' as is usual in the double breasted style. The width of the flaps 16', 17' is optional.

To maintain the extension of the flaps 16', 17' and to prevent them from curling, a stiffness is imposed on them and on about an equal area abutting them respectively, of the panels 16 and 17. So the area A, B, C, D on each front garment part, is stiffened by applying a suitable stiffening means in face-to-face adhesion with the back surface thereof, which may be accomplished by applying a plastic coated pliable sheet 25 and bonding it thereto by pressure and heat. This will maintain the smoothness of the front and proper suspension of the free edges of the flaps 16', 17'. Numeral 26 denotes the garment's inner lining.

Although the garment illustrated is a man's jacket, the teachings of this invention may be equally applied to jackets and long coats for men, women and children, with appropriate styling effects as are incident thereto. All these shall be deemed to be included in the term "garment" as used in the appended claims.

This invention is capable of numerous forms and various applications without departing from the essential features herein disclosed. It is therefore intended and desired that the embodiment shown herein shall be deemed merely illustrative and not restrictive and that the patent shall cover all patentable novelty herein set forth; reference being had to the following claims rather than to the specific showing and description herein to indicate the scope of this invention.

I claim:

1. A buttoned in the front garment of the character described, having a collar and inverted, substantially triangular-shaped lapels extending respectively from the ends of the collar downwardly substantially to the waist line region of the garment; the lower extremity of each lapel being a vertex; said vertices coinciding at a point on

the vertical center line of the front of the garment; said garment including a right front panel and a left front panel which are folded over to form said lapels; the right front panel having a substantially rectangular flap in extension thereof downwardly from said point to the bottom edge of the garment, and horizontally a predetermined distance from said center line towards the left side of the garment; the left front panel having a substantially rectangular flap in extension thereof downwardly from said point to the bottom edge of the garment, and horizontally a predetermined distance from said center line towards the right side of the garment; one of said flaps having a button hole near its top edge and overlapping the front surface of the panel other than the one it extends from; the other flap underlapping the back surface of the panel other than the one it extends from, and a button on the front surface of the underlapped panel to releasably engage said button hole, whereby the structure of the garment is of the single breasted type from said point upwards, and of the double breasted type from said point downwards.

2. A garment as defined in claim 1, wherein the gen-

eral plane of the entire bottom edge of the garment is horizontal.

3. A garment as defined in claim 1, including means in back of each flap for stiffening said flaps respectively against curling.

4. A garment as defined in claim 3, wherein each of said means comprises a pliable layer of stiffening quality, in face to face contact with at least the entire surface of the flaps respectively.

5. A garment as defined in claim 4, wherein said layer is bonded in face-to-face adhesion with its associated flap.
